(57) **CLAIM**

The ornamental design for an educational game board game piece, as shown and described.

DESCRIPTION

FIG. 1 is a perspective view of a game piece according to the present invention.

FIG. 2 is a front view of the game piece of FIG. 1.

FIG. 3 is a back view of the game piece of FIG. 1.

FIG. 4 is a first side view of the game piece of FIG. 1.

FIG. 5 is a second side view of the game piece of FIG. 1.

FIG. 6 is a top view of the game piece of FIG. 1; and,

FIG. 7 is a bottom view of the game piece of FIG. 1.

The broken lines depict environmental subject matter and form no part of the claimed design.
